UNITED STATES PATENT OFFICE

CARL A. LANDIN, OF HARTFORD, CONNECTICUT, ASSIGNOR TO THE HART MANUFACTURING COMPANY, OF HARTFORD, CONNECTICUT, A CORPORATION OF CONNECTICUT

SWITCH

Application filed June 12, 1930. Serial No. 460,685.

This invention has to do broadly with electric switches, and is more particularly concerned with that type of switch which includes an operating member which serves to indicate the condition of the switch.

The above noted type of switch is today meeting with widespread use in the field of electric ranges and cooking instrumentalities. Owing to the fact that it is of importance for the user of an electric range to be able to readily determine whether it is off or on, and if the latter is the case to what degree the heat is being applied, it has become standard practice in this art to so mount the control switch for electric ranges and the like on the ranges themselves with the operating member of the switch arranged so that when it points upwardly the switch is in its off position. From this off position a turning of the switch in a clockwise direction will gradually cause the heat to be applied in varying degrees. Normally one of these switches provides for an off position and three heating positions, low, medium, and high, all of which positions are spaced substantially ninety degrees apart.

Switches of this sort are mounted on ranges and the like in different manners, depending upon the requirements of the trade, or the design of the particular manufacturer of products including a switch.

That is to say, the requirements in some instances are such that the switches have a predetermined angular position, and in other instances the switch will have a different angular position, and it is important, in order to meet these various requirements, to have a switch adaptable to use under varying conditions. Moreover, it is highly desirable for a manufacturer of the switches to be able to carry in stock one switch which will answer the varying conditions of installment of the trade.

Bearing this condition in mind, this invention has in view, as its primary object, the provision of a switch of the above noted type which includes an operating member, together with suitable means for adjusting the operating member with respect to the remainder of the switch mechanism so that it may point upwardly to indicate the off position regardless of just where or how the switch itself is mounted on an electric range or the like.

The invention also has, as an important

feature thereof, the provision of an operating member for switches of the above noted type which may be readily operatively connected to switches now being made without any substantial modification in the construction of the latter. The invention wishes to avoid any radical departure from the present design of the switches as a whole, but rather contemplates a slight change in the construction of the mechanism which operatively connects the operating member with the switch to provide the advantageous results above noted.

Furthermore, the invention has in view the provision of connections for the operating member of the switch hereinbefore mentioned which are of a highly simplified construction and which may be readily assembled with the remainder of the switch mechanism.

Other objects will be in part obvious and in part pointed out more in detail herein-after.

The invention accordingly consists in the features of construction, combination of elements and arrangement of parts which will be exemplified in the construction herein-after set forth and the scope of the application of which will be indicated in the appended claims.

For a full and more complete understanding of the invention reference may be had to the following description and accompanying drawing, wherein:

Figure 1 is a section through the operating member of a switch, together with associated parts, embodying the improvements of this invention. This view is taken about on the plane represented by the line 1—1 of Figure 2.

Figure 2 is a bottom plan view section on line 2—2 of Figure 1 showing the operating member per se with the connecting parts shown.

Figure 3 is a view similar to Figure 1 and taken about on the same plane as Figure 1 but with the connections for operatively connecting the operating member to a switch omitted.

Figure 4 is a section taken about on the plane represented by the line 4—4 of Figure 2 and showing the connections as they are being adjusted by a suitable tool.

Figure 5 is a group perspective of the op-

erating member, together with the various parts entering into the connection of the operating member with the switch and

5 Figure 6 is a perspective of one end of a tool which may be employed to adjust the operating member of the switch.

A switch adapted to receive and embody the improvements of this invention is clearly 10 illustrated and described in the co-pending application of Hart, Serial Number 308,979, filed September 28, 1929, and such a switch is not, therefore, herein illustrated. It suffices to say that a switch of the type described in the co-pending application is primarily 15 designed for use on electric ranges and other electrical cooking instrumentalities and is characterized as having four distinct conditions which it may assume, depending on the position of the operating member. In 20 one position all current to the electric range is cut off. This is what is known as the off position. In a second position, which is assumed when the operating member is at an angle of substantially ninety degrees, in a 25 clockwise direction, from that assumed by it when in the off position, the switch provides the current for a low heat in the cooking instrumentality. When the operating member is turned an additional quarter revolution 30 the switch assumes the condition wherein the current supplied to the heaters provides for a medium heat. Still another partial revolution of ninety degrees, in a clockwise direction of course, causes the switch to assume 35 the position supplying an electric current for a high heat in the cooking instrumentality. When the operating member is turned ninety degrees from this high position it is brought back to the off position.

40 A switch, such as is shown and described in the copending application of Hart referred to ordinarily includes a spindle referred to as 10 and a driven member secured to the spindle. In the present instance, the 45 driven member is shown, for illustrative purposes, as comprising a hub or sleeve-like member 11 which is mounted on a plate 12, which in turn is positively fastened to the spindle 10, and these parts 11 and 12 constitute the 50 controlling parts for the switch. That is, when the hub 11 is turned in one position, the spindle 10 is turned and one of the conditions described in the preceding paragraph is assumed, and turning the same ninety degrees will cause the other conditions to be assumed in their regular order.

55 In accordance with the present invention, a handle or operating member 13, which is made in the shape of a pointer as clearly 60 shown in Figure 2 and which has the point 14, is operatively connected to the hub 11 in such a manner as to permit of adjustment between the operating member 13 and the hub 11, and at the same time provide for a 65 non-rotatable or driving connection between

these parts when they are assembled. The hub 11 is formed with a vertically extending slot 15 which extends through a top or end member 16 carried on the upper end of the hub 11. The member 16 may be integrally 70 formed with the hub 11 or connected thereto in any preferred manner, and is provided with a threaded opening as indicated at 17. A nut 18 is threaded on the reduced shank 19 of the stem 10 and serves to positively position the hub 11 and plate 12 with respect to the spindle 10.

The operating member 13 is of a recessed construction as clearly shown in the drawing. This construction may be described as 80 comprising a main recess or hollow 20 which is cutaway at diametrically opposite sides to provide grooves 21 extending substantially the entire depth of the recess 20, there being a seat 22 formed on the bottom of the recess 20. Spaced an appreciable distance from the open end of the recess 20 the operating member 13 is provided with a circular groove or circumferential channel 23 which, of course, cuts across and communicates with the longitudinal grooves 21. The groove or channel 23 defines a shoulder which is formed due to the fact that the recess 20 is enlarged in diameter from the circular groove to the open end of the recess. A shallower circular groove 24 is also formed in the bottom portion of the member 13 at a point still nearer the mouth of the recess 20. Located intermediate the grooves 21 on each side of the opening 20 are two grooves 25 which extend from the open end of the recess 20 down to the circular groove 23.

Referring now more particularly to Figures 1 and 5, a hollow shank is shown at 26 as provided with threads 27 for a portion of its length. Fastened to one end of the shank 26 is a plate member 28 having diametrically opposed lugs 29 which are adapted to fit in the grooves 21 in the member 13 whereby relative rotation between the threaded shank 26 and the member 13 is prevented. A coil spring 30 of suitable design is located in the recess 20 and surrounds the shank 26 and bears against the plate 28 at one end and against a ring member 31 at the other end. The ring member 31 is provided with four lugs 32 which are equidistantly spaced apart about the periphery thereof. Obviously, the annular distance between these lugs is ninety degrees. These lugs are normally maintained out of the circular groove 23 and in the longitudinal grooves 21 and 25 by the spring 30, and when these lugs 32 are located in the grooves 21 and 25 relative rotation between the ring member 31 and the operating member 13 is positively prevented. However, when the ring member 31 is moved downwardly towards the bottom of the recess 20 (upwardly with respect to the showings of Figures 1 and 3) the lugs 32 are 125 130

moved into the circular groove 23, whereupon the ring member 31 may be rotated with respect to the member 13.

The ring member 31 which may be referred to as a connecting member, is provided with a cylindrical flange 33 that is formed with a lug 34 which projects radially inwardly and fits into the slot 15 when the operating member is assembled on the switch. It is evident that when the lug 34 is positioned in the slot 15 and the lugs 32 are fitted in the grooves 21 and 25 a non-rotatable or driving connection between the operating member 13 and the hub 11 is provided.

15 A retaining member 35 has a ringlike flange 36 which at times serves as an abutment for the ring member 31 when the latter is urged outwardly of the recess 20 under the influence of the spring 30. The retaining member 35 is also formed with fingers 37 which may be bent over to retain a washer 38 in position against the bottom face of the operating member 13. A spring clip in the form of a split ring 39 is partially seated in 25 the groove 24 and has a portion projecting radially inwardly which engages the flange 36 of the retaining member 35 to prevent the latter from being moved out of the recess 20 by the spring 30.

30 In assembling the above noted instrumentalities, the threaded shank 26 is first positioned in the recess 20 by properly locating the lugs 29 in the grooves 21, whereupon the plate 28 may be moved to the bottom of the recess 20. The coil spring 30 is then positioned about the shank 26, after which the ring member 31 is fitted in the opening by causing the lugs 32 to enter into the grooves 21 and 25. This retaining member is moved 35 down to a point past the groove 24, after which the retaining member 35 is fitted in the opening. The spring ring 39 is now positioned in the groove 24 and serves to hold the parts just described in their assembled 40 relation.

It is evident that the position of the lug 34 on the ring member 31 relative to the point 45 of the operating member 13 is the controlling factor as to the positioning of the latter with respect to the switch and the off position thereof. This member 34 fits in the groove 15 and when so positioned establishes the driving connection between the operating member 13 and the switch mechanism. 50 The above described construction provides for the adjustment of the lug 34 with respect to the operating member 13, and which adjustment may be effected by the use of some tool such as that shown in Figure 6.

55 This tool, which is referred to as 50, is preferably hollow, as shown at 51, and cut away at one end to provide a shoulder 52. A notch 53 extends through both the cutaway and main portions of the tool 50 and is designed to receive the lug 34. In using the

tool 50 to adjust the lug 34 with respect to the operating member 13, the hollow end of the tool is first inserted so that the hollow end receives the threaded shank 26 and the notch 53 receives the lug 34. The shoulder 70 52 engages the cylindrical portion 33 of the ring member 31 so that the latter is moved downwardly in the opening 20 (upwardly with respect to Figures 1 and 3) so as to cause the lugs 32 to enter the groove 23. The tool 75 may now be turned through the required annular distance to cause the lugs 32 to become aligned with the grooves 21 and 25 so that the lug 34 is properly positioned. When this alignment has been obtained a removal of the 80 tool permits the spring 30 to urge the ring member 31 outwardly of the recess 20, whereupon the lugs 32 enter their respective grooves 21 and 25 to establish the non-rotatable connection between the ring member 85 and the member 13.

The above described operating member and associated parts are connected to the hub 11 by screwing the threaded portion of the shank 26 into the threaded opening 17 in the plate 90 16. This is carried out until the lug 34 enters the groove 15, and may be further carried out to cause the lug 34 to be seated the proper distance in the slot 15 by compressing the spring 30 sufficiently to maintain the lug 95 34 out of the groove 15 until the parts 26 and 16 have been threaded together sufficiently far to cause the lug 34 to be properly seated when the spring is released. The compression of the spring 30 is effected by merely pulling outwardly on the operating member 13, which causes the plate member 28 to move outwardly of the socket member 20, whereby the spring is compressed. It is preferable to screw the threaded portion 27 of the 100 shank 26 entirely through the plate 16 by the above described operation so as to insure of the proper seating of the lug 34 in the slot 15.

When it is desired to adjust the lug 34 so 110 as to provide for the pointer 14 being in an upward position, regardless of the manner in which the switch has been applied to an electric range, it is necessary to first remove the operating member 13, together with the instrumentalities located in the socket 20, from the sleeve 11. This is a comparatively simple operation, as all that is necessary is to unscrew the shank 26 from the plate 16, which operation is permitted upon compression of 115 the spring 30 sufficiently far to cause the lug 34 to be moved out of the slot 15 in which it is positioned. After removal of the operating member the lug 34 may be adjusted 120 in the manner above described.

The foregoing arrangement is not only of a comparatively simple construction from the manufacturer's viewpoint, but also provides for a simple operation by the installer of the switch after it leaves the manufac- 130

turer's hands. Any person installing the switch can readily adjust the lug 34 with respect to the operating member 13 through the use of a tool such as the one shown in 5 Figure 5, no skill being required to effect this adjustment. Moreover, proper operation of the switch when applied is insured, due to the fact that the lug 34 can be adjusted only upon removal of the operating member 10 13 from the switch, there being no positive relative movement between these parts when the switch and operating member are completely assembled.

It is further evident that the operating 15 member 13, together with its associated parts, may be substituted in lieu of any of the operating members now assembled with switches of the type shown in the co-pending application of Hart.

20 As many changes could be made in the above construction and many apparently widely different embodiments of this invention could be made without departing from the scope thereof, it is intended that all matter 25 contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, 35 might be said to fall therebetween.

What is claimed is:

1. An electric switch of the character described comprising a switch mechanism adapted to assume a plurality of positions 40 whereby current supply to an electric range or the like is controlled, one of said positions being off, and an operating member for the switch mechanism, said operating member also constituting indicating means for indicating the position of the switch, said operating member being recessed, means in said recess for establishing a driving connection between the operating member and the switch mechanism, and means within said recess for 45 permitting the varying of the position of the operating member with respect to the switch mechanism while each of said means is disposed within the recess.

2. An electric switch of the character described comprising a switch mechanism having a spindle and a driven member fixed thereto, a handle constituting a pointer and having a recess adapted to receive the end of 50 said spindle, a connecting member within said recess and having a detachable interlock with said driven member, said connecting member and handle having interengaging means whereby the connecting member may be secured in various angular positions against 55 rotation with respect to the handle, and

means within said recess for permitting the varying of the position of the connecting member with respect to said handle while said connecting member is disposed within the recess. 70

3. An electric switch of the character described comprising a switch mechanism having a spindle and a driven member fixed thereto, a handle having a recess adapted to receive the end of said spindle, a connecting member within said recess and having a detachable interlock with said driven member, said handle and connecting member having detachable interlocking means for securing the connecting member in various angular positions against rotation to the handle, said connecting member being longitudinally movable in said recess to an inoperative position where said interlocking means between the connecting member and handle are disengaged, and means within said recess for permitting the varying of the position of the connecting member with respect to the handle when the connecting member is in inoperative position and while said connecting member is disposed within the recess. 80

4. An electric switch of the character described comprising a switch mechanism having a spindle and a driven member fixed thereto, a handle having a pointer, a connecting member located in said handle and having a detachable interlock with said driven member, said handle and connecting member having means whereby the connecting member may be interlocked with said handle 95 100 in various angular positions, said connecting member being movable into and out of interlocking relation to the handle, and means within said recess for permitting the varying of the position of the connecting member with respect to the handle when the connecting member is in non-interlocking position and while said connecting member is disposed within said handle. 105

5. An electric switch of the character described comprising a switch mechanism having a spindle and a driven member fixed thereto, a handle constituting a pointer and having a recess adapted to receive the end of said spindle, a connecting member within said recess and having a detachable interlock with said driven member, said connecting member having a lug and said recess having a plurality of angularly spaced grooves in which said lug is adapted to selectively engage, said recess having a circumferential channel to which said grooves lead, said connecting member when located in the plane of said channel being adjustable, and means for urging said connecting member out of said plane to engage the lug thereof in one of said grooves. 110 115 120

6. An electric switch of the character described comprising a switch mechanism having a spindle and a driven member fixed 125 130

- thereto, a handle constituting a pointer and having a recess provided with longitudinally extending grooves and a circumferential channel, a connecting member having a detachable interlock with said driven member, said connecting member having a lug adapted to selectively engage in said longitudinal grooves, said connecting member being movable axially of said recess and being angularly adjustable when in the plane of said channel, and means for yieldingly maintaining the connecting member in a position where said lug is engaged in one of said grooves. 70
- 10 7. An electric switch of the character described comprising a switch mechanism having a spindle and a driven member fixed thereto, a handle constituting a pointer and having a recess provided with longitudinally extending grooves and a circumferential channel, a connecting member in said recess and having a detachable interlock with said driven member, said connecting member having lugs adapted to selectively fit in said grooves, said connecting member being movable axially in said recess, and means for retaining said connecting member in said recess. 80
- 15 8. An electric switch comprising a switch mechanism having a spindle and a driven member fixed thereto, a handle constituting a pointer and having a recess provided with a circumferential channel and grooves extending longitudinally therefrom, a connecting member located in said recess and having lugs adapted to engage in said grooves, spring means for maintaining said connecting member in a position where the lugs are engaged in said grooves, said connecting member having a part adapted to interlock with said driven member, said connecting member being movable inwardly in said recess to a position where it is in the plane of said channel, and a washer closing a part of the open end of said recess. 90
- 20 9. A handle for use in connection with switches having a spindle provided with a driven member and including a handle member having a recess provided with longitudinally extending grooves and a circumferential channel, a shank or the like slidably mounted in said recess and held against rotation relative to said handle member, a spring normally holding the handle member against longitudinal movement relative to said shank, a connecting member in said recess and having a detachable interlock with said driven member, said connecting member having lugs adapted to selectively engage in said grooves, said connecting member being movable into the plane of said channel where it may be angularly adjusted with respect to the handle, and a retaining member in said recess on which said connecting member is adapted to seat. 100
- 25 10. A handle for use in connection with switches having a rotary spindle provided with a driven member and including a handle member having a recess provided with annularly spaced apart grooves, and a circumferential channel connecting the grooves, a connecting member in said recess and having a lug adapted to selectively engage in said grooves and also having a part adapted to be detachably interlocked with the driven member, and means for supporting said connecting member in a position where the lug thereof is engaged in a groove, said connecting member being movable into the plane of said channel to permit of angular adjustment between the handle member and the connecting member. 110
- 30 11. A handle for use in connection with switches having a rotary spindle provided with a driven member and including an indicating handle member provided with a recess having a circumferential channel adjacent the open end thereof, said recess also being formed with longitudinally extending grooves leading to said channel, a connecting member having lugs adapted to fit in said grooves, said connecting member also having a part adapted to interlock with said driven member, means for retaining said connecting member in said recess, and a spring bearing upon said connecting member, said connecting member being angularly adjustable when in the plane of said channel. 120
- 35 12. In an electric switch, an operating member having an indicating pointer and provided with a recess the walls of which are formed with a circumferential channel, the walls of said recess also being formed with longitudinally extending grooves leading to said channel, a shank or the like slidably mounted in said recess and held against rotation relative to said handle, a spring normally holding the handle member against longitudinal movement relative to said shank, a connecting member within said recess and against which one end of said spring is adapted to bear, said connecting member having lugs adapted to selectively engage in said grooves, said connecting member being movable into the plane of said channel where it may be angularly adjusted with respect to the handle, and a retaining member in said recess on which said connecting member is adapted to seat. 130

CARL A. LANDIN.
